UNITED STATES PATENT OFFICE

JOHN ROY DEW, OF SOUTH JACKSONVILLE, FLORIDA, AND ROY GUFFEY, OF SOMERSET, KENTUCKY

DESIGN FOR A FERNERY STAND

Application filed January 6, 1930. Serial No. 34,035. Term of patent 14 years.

To all whom it may concern:

Be it known that we, JOHN R. DEW and Roy GUFFEY, citizens of the United States, residing, the said DEW at South Jacksonville, Duval County, Florida, and the said GUFFEY at Somerset, in the county of Pulaski and State of Kentucky, have invented a certain new, original, and ornamental Design for Fernery Stands, of which the following is a specification.

The figure is a perspective view of a fernery stand, showing our new design.

We claim:

The ornamental design for a fernery stand, as shown.

In witness whereof, we have hereunto set our hands at Jacksonville, Florida, this 4th day of January, A. D. nineteen hundred and thirty.

ROY GUFFEY.

JOHN ROY DEW.
